METHOD OF TREATING AND PURIFYING
MOTOR FUELS

William M. Stratford, New York, N. Y., assignor
to The Texas Company, New York, N. Y., a cor-
poration of Delaware

No Drawing. Application January 25, 1932,
Serial No. 588,823

5 Claims. (Cl. 196—13)

This invention relates to the treatment of hydrocarbon distillates such, for example, as cracked petroleum naphtha and like motor fuels. More particularly, the invention relates to a method of treating and purifying oils such as petroleum naphthas and the like by extraction with a material comprising furfural, whereby gum-forming and other undesirable constituents are separated from the oil and the treated oil rendered stable and more desirable in character.

Ordinarily the lighter distillate hydrocarbons, such for example as petroleum naphtha, having a boiling range suitable for motor fuel, contain undesirable constituents such as sulfur compounds and materials which tend to form gummy deposits in the distillates over a period of time. This is particularly true of distillates such as cracked naphtha derived from the pyrogenic decomposition of petroleum by the well-known cracking processes in general use today.

The ordinary method of refining such distillate oils to reduce the content of undesirable sulfur compounds and gum-forming constituents includes treatment with strong sulfuric acid and alkali, followed by treatment with sodium plumbite solution (the so-called "doctor" solution) and redistillation. Such ordinary methods of treatment have certain disadvantages, including the cost of chemicals and of the redistillation of the treated oil. One of the more important disadvantages resulting from such treatment is the loss of desirable constituents from the oil, the presence of which render the oil resistant to the well-known knocking phenomena observed in high compression internal combustion engines. This resistance to knocking, or the "anti-knock" value of the fuel as it is referred to in the current literature, is at the present time expressed in units representing the octane number of the oil. The basis of this representation is so well known as to require no explanation here. It is sufficient to state that the ordinary acid and alkali treatment, followed by distillation, applied to a naphtha of high octane number, particularly naphthas produced by cracking at the higher temperatures, results in a material lowering of the octane number of the oil, with corresponding lowering of its quality.

In the practice of the present invention, which involves the extraction of undesirable sulfur compounds and gum-forming constituents from oil such as cracked naphtha by material comprising furfural, the disadvantages of the ordinary acid, alkali and distillation treatment may be substantially avoided, and the purified motor fuel may be

produced at a materially lower cost of treatment without substantial reduction in the octane number of the fuel.

In the practice of the invention the procedure includes the intimate mixing and agitation of the oil or naphtha to be purified with a material comprising furfural. Preferably this material will be a mixture of furfural and water, the exact composition of which may be varied to produce a graduated selective action upon the oil undergoing treatment. For example, the oil may be agitated with an equal quantity of ordinary commercial furfural saturated with water, which is a composition containing about 94% furfural and about 6% of water. Such treatment when carried out at ordinary room temperature of about 70°—80° F., results in the extraction of approximately 10% by volume from naphtha derived from an ordinary commercial type of cracking process, such for example as the well-known Holmes-Manley process. The resulting naphtha, when washed free from traces of furfural, is materially improved in that constituents tending to form gum are substantially reduced, as well as the sulfur content of the oil.

The selective action of the furfural reagent in extracting certain constituents from the oil may be varied, both by a variation in the concentration of furfural used, and by a variation in the temperature of treatment.

Thus, while a particular concentration of 94% furfural and 6% water has been described as applied at a temperature of about 70°—80° F., the concentration of water in the reagent may be increased, which will bring about a corresponding lesser degree of extraction from the oil undergoing treatment. On the other hand, using a fixed concentration of a furfural-water mixture, the degree of extraction from the oil may be varied by varying the temperature under which the extraction takes place. Thus, the quantity of extract from the oil undergoing treatment will increase with an increase in temperature, and decrease with a decrease in temperature, depending upon the individual characteristics of the oil undergoing treatment. Extraction temperatures as low as 0° F. may be found desirable, and as high as 200° F. or more. In the latter case, that is, where higher temperatures are used, it is desirable to carry on the extraction under super-atmospheric pressure to prevent evaporation of the oil and reagent during the treatment.

The quantity of furfural or reagent comprising furfural which is used in the extracting treatment may be varied in accordance with the indi-

- vidual characteristics of the oil undergoing treatment. For example, in the case of some types of oils it may be preferable to extract the oil with a comparatively large volume, say several hundred 5 per cent, of 94% furfural at ordinary temperatures, while in the case of other oils it may be desirable to extract with a comparatively small volume, say less than an equal volume of a more concentrated furfural reagent at temperatures 10 well above normal atmospheric temperature.
- Although furfural and mixtures of furfural with comparatively small quantities of water have been mentioned specifically as suitable extracting reagents, other mixtures may be found effective, 15 particularly when applied to oils of unusual characteristics. For example mixtures of furfural with other polar substances, such as alcohol and the like, in varying proportions are found to have a selective solvent action to a different degree 20 upon undesirable constituents of certain oils.
- Under ordinary conditions the extraction treatment with a reagent comprising furfural which is described herein may be applied to a raw distillate oil to produce a finished merchantable product. However, in the case of oils of exceeding high sulfur content or unusual characteristics as regards tendency to form gum, it 25 may be found desirable to supplement the furfural treatment by the usual acid, alkali and doctor treatment applied either before or after the furfural treatment. Also in many cases it may be found desirable to treat the oil, after extraction with the furfural reagent, with a solution of sodium plumbite.
- 30 The material extracted from the oil by the furfural reagent may, after separation of the furfural reagent, be subjected to refining treatment as for example distillation, acid treatment, or treatment to effect desulfurization, and may thereafter be used for various purposes. If sufficiently refined 35 it may be blended with the purified motor fuel from which it was originally separated.
- Although the extraction treatment with a material comprising furfural has been discussed particularly in connection with the treatment of oils 40 such as cracked petroleum naphthas and the like, the method of treatment is also applicable to other types of oils, such for example as straight-run naphthas from crude oils of asphaltic characteristics and those having particularly high sulfur content, also shale oils and the like.
- Obviously many modifications and variations 45 of the invention, as hereinbefore set forth, may be made without departing from the spirit and scope thereof, and therefore only such limitations should be imposed as are indicated in the appended claims.
- I claim:
1. The method of treating and purifying 50 cracked petroleum naphtha for the production of motor fuel comprising extracting the naphtha with a material comprising a mixture of furfural and water in proportions to each other and to the naphtha adapted to remove around 10% by vol-

ume of the original naphtha as an extract containing gum-forming constituents and undesirable sulphur bodies without substantial impairment of the anti-knock value of the naphtha.

2. The method of treating and purifying 5 cracked petroleum naphtha for the production of motor fuel comprising extracting the naphtha with a mixture comprising furfural saturated with water at a temperature of about 70° F. to 80° F. and adapted at such temperatures to separate 10 from the naphtha around 10% by volume as an extract whereby gum-forming constituents and undesirable sulphur bodies are removed without substantial impairment of the anti-knock value of the naphtha.

3. The method of treating and purifying petroleum naphtha for the production of motor fuel which comprises mixing with the naphtha a solvent comprising a mixture of furfural substantially saturated with water at around 70° F. to 80° F. 20 and adapted at such temperatures to separate from a light distillate of the character of cracked naphtha around 10% by volume of material including gum forming constituents as an extract soluble in the solvent mixture, maintaining the 25 mixture under suitable conditions of temperature to effect separation of the naphtha into a fraction substantially insoluble in the solvent and comprising the desired motor fuel product and a fraction soluble in the solvent and containing 30 the undesired extracted constituents, and removing the separated extracted constituents from the solvent treated naphtha.

4. The method of treating and purifying petroleum naphtha for the production of motor 35 fuel which comprises mixing with the naphtha a solvent comprising a mixture of furfural and water and adapted at temperatures of around 70° F. to 80° F. to separate from a light distillate of the character of cracked naphtha around 10% 40 by volume of material including gum forming constituents as an extract soluble in the solvent mixture, maintaining the mixture at a temperature within the range of 0° F. to around 200° F. to effect separation of the naphtha into a fraction 45 substantially insoluble in the solvent and comprising the desired motor fuel product and a fraction soluble in the solvent and containing the undesired extracted constituents, and removing the separated extracted constituents from the 50 solvent treated naphtha.

5. The method of treating and purifying cracked petroleum naphtha for the production of motor fuel, comprising extracting the naphtha with a solvent comprising furfural in admixture 55 with a polar substance containing a hydroxyl group and of the character of water and alcohol, in proportion to the furfural and to the naphtha adapted to remove around 10% by volume of the original naphtha as an extract containing gum forming constituents and undesirable sulphur bodies without substantial impairment of the anti-knock value of the naphtha.

WILLIAM M. STRATFORD.
